FIG. 1

FIG. 5

FIG. 2

FIG. 6

FIG. 3

FIG. 7

FIG. 4

FIG. 8

FIG. 1 is a top perspective view of a hair waving rod showing my new design with the locking end portion being disengaged from the right remote end thereof;

FIG. 2 is a top plan view thereof;

FIG. 3 is a side elevational view, the side opposite being a mirror image thereof;

FIG. 4 is a bottom plan view;

FIG. 5 is an end elevational view of the right end of FIG. 2;

FIG. 6 is an end elevational view of the left end of FIG. 2;

FIG. 7 is an enlarged cross sectional view taken laterally through the aligned openings of the design of FIG. 1; and

FIG. 8 is a top perspective view of a second embodiment of my design on which the end portions meet the portion therebetween in a flush manner and the portion

therebetween is similar on all sides and without openings.

I claim:

The ornamental design for hair waving rods, substantially as shown and described.
